(74) *Attorney, Agent, or Firm* — Todd R. Fronek; Larkin Hoffman Daly & Lindgren, Ltd.

(57) **CLAIM**

The ornamental design for a medication dispenser, as shown and described.

DESCRIPTION

FIG. 1 is an isometric view of a medication dispenser.

FIG. 2 is a top plan view of the medication dispenser of FIG. 1.

FIG. 3 is a bottom plan view of the medication dispenser of FIG. 1.

FIG. 4 is a front plan view of the medication dispenser of FIG. 1.

FIG. 5 is a rear plan view of the medication dispenser of FIG. 1.

FIG. 6 is a left plan view of the medication dispenser of FIG. 1; and,

FIG. 7 is a right plan view of the medical dispenser of FIG. 1.

The broken lines depict portions of the article that form no part of the claimed design.

1 Claim, 7 Drawing Sheets
